UNITED STATES PATENT OFFICE.

NICHOLAS S. VEDDER, OF TROY, AND TOBIAS S. HEISTER, OF LANSINGBURG,
ASSIGNORS TO NICHOLAS S. VEDDER, OF TROY, NEW YORK.

DESIGN FOR A PARLOR COOKING-STOVE.

Specification forming part of Design No. 6,311, dated December 17, 1872.

To all whom it may concern:

Be it known that we, NICHOLAS S. VEDDER, of the city of Troy, in the county of Rensselaer and State of New York, and TOBIAS S. HEISTER, of Lansingburg, in said county and State, have jointly invented and produced a new and original Design for Parlor Cooking-Stoves, of which the following is a specification, reference being had to the accompanying wood cut or engraving of a stove which embodies our said design.

One part of our invention consists of the ornamental design of the cover V, as represented in the aforesaid wood-cut. Another part consists of the ornamental design for the top plate W, as shown in the cut. Another part consists of the design for the upper front plate X, as distinguished by the ornamentation y z y thereon, as shown in the engraving. Another part consists of the design for the upper end plate A, as characterized by the striped panel-surface b, border-molding c, and ornaments d, all combined so as to appear substantially as represented in the engraving. Another part consists of the design for the doors E, as distinguished by the striped surface-panel f and ornamented border-molding g thereon, as represented in the wood-cut. Another part consists of the design for the plate H, substantially as shown in the aforesaid engraving. Another part consists of the design for the lower front plate I,

as distinguished by the projecting end portions j, ornamented as shown in the engraving. Another part consists of the compound panel-ornament K, shaped and arranged on a plate or door of a stove, substantially as shown in the aforesaid engraving. Another part consists of the design for the bottom plate L, as distinguished by the ornamented moldings m and n, with or without the ornaments o o thereon.

What we claim as our invention is—

1. The design for the cover V, as above specified.
2. The design for the top plate W, as set forth.
3. The design for the upper front plate X, as described.
4. The design for the upper end plate A, as set forth.
5. The design for the doors E, as described.
6. The design for the plate H, as specified.
7. The design for the lower front I, as described.
8. The design for the panel-ornament K, as set forth.
9. The design for the bottom plate L, as described.

NICHOLAS S. VEDDER.
TOBIAS S. HEISTER.
